3 Claims. (Cl. 333—95)

Helical-walled circular waveguides are known which comprise a dielectric substance which is disposed between the helical wall and a screen consisting of a tube of metal fabric, the assembly being covered by an external protective sheathing. Such guides effect the transmission of waves of the TE₀₁ type, while producing a considerable attenuation of other types of waves.

It has been observed, both theoretically and experimentally that this attenuation is maximum when the distance between the metal screen and the external surface of the helical wire is equal to a quarter radial wavelength in the interposed dielectric substance. It follows that the attenuation to which waves of undesirable types are subjected by such a waveguide is maximum for a given frequency and decreases on either side of the latter which leaves only a narrow useful frequency band. However, it has been shown that it is possible to extend the filtering band of such guides by embedding in the dielectric substance, within the aforesaid screen, one or more semi-reflecting layers, but the useful band width remains limited to less than one octave, which may cause difficulties in extending the use of circular waveguides in telecommunications.

The present invention relates to a helical waveguide of which the filtering effect on parasitic modes retains a maximum value in a very wide frequency range, which may reach a number of octaves, without the quality of this filtering being inferior to that obtained under the best conditions by previously known means. Such a result can be obtained only if the dielectric medium disposed between the metallic screen and the outer surface of the helical wire always constitutes, for electromagnetic waves excited by the undesirable modes, an electrical path equal to one quarter of a radial wavelength λ_r or to an odd multiple of $\frac{1}{4} \lambda_r$ in the material under consideration, regardless of the frequency employed. This may be achieved only if the radial dielectric constant ϵ_r of the interposed material satisfies the condition

$$\frac{\lambda_0}{4(2K+1)\sqrt{\epsilon_r}} = \text{constant} = d$$

d denoting the thickness of this material, K being an integer and λ_0 denoting the wavelength in vacuo at the frequency f under consideration.

This condition may be written:

$$\epsilon_r = \frac{c^2}{16(2K+1)^2 \omega^2 f^2}$$

c denoting the velocity of light in vacuo:
 $c=3.10^8 \text{ MKS}$

The waveguide according to the present invention is characterised by the fact that the dielectric disposed between the wire and the screen comprises insulating materials containing polar molecules and having ferroelec-

2

tric properties, so chosen that the relaxation phenomena of the molecules of the dielectric occur in the frequency band in which the guide is used. It is known that the effective dielectric constant ϵ' of such materials may be placed in the form

$$\epsilon' = \epsilon_\infty + \frac{\epsilon_s - \epsilon_\infty}{1 + \left(\frac{\epsilon_s + \epsilon_0}{\epsilon_\infty + 2\epsilon_0} \right)^2 \omega^2 t^2}$$

10 ∞ denoting the dielectric constant at infinite frequency (corresponding, for example, to visible light), ϵ_s the static dielectric constant (measured at very low frequency), t the relaxation time of the material under consideration, ϵ_0 the dielectric constant of a vacuum and ω the pulsation $= 2\pi f$ at the frequency under consideration.

It is found that if the frequency is sufficiently high to have

$$\left(\frac{\epsilon_s + 2\epsilon_0}{\epsilon_\infty + 2\epsilon_0} \right)^2 \omega^2 t^2 \gg 1$$

and if the material has a sufficiently high static dielectric constant ϵ_s , this relation is reduced substantially to:

$$\epsilon' = \frac{\epsilon_s - \epsilon_\infty}{\left(\frac{\epsilon_s + \epsilon_0}{\epsilon_\infty + 2\epsilon_0} \right)^2 \omega^2 t^2}$$

It is then sufficient to choose the thickness d in such manner that the desired relation is satisfied, by writing:

$$\frac{\epsilon_s - \epsilon_\infty}{\left(\frac{\epsilon_s + 2\epsilon_0}{\epsilon_\infty + 2\epsilon_0} \right)^2 \pi^2 t^2} = \frac{c^2}{4\epsilon^2 (2K+1)^2}$$

35 By way of non-limiting example, the material incorporated in the filling dielectric is chosen from the plumbates, the titanates, the niobates, the tantalates, the tungstates, etc., of alkaline-earth metals, all of which substances have very pronounced ferroelectric properties, while the relaxation phenomena are generally manifested in the centimetric or the millimetric wave range, which are precisely utilised for transmission by circular waveguides. However, some organic substances having polar molecules, such as aluminium-guanidine sulphate, may also constitute dielectrics having appropriate characteristics, because the relaxation phenomenon is extremely widespread.

40 The substances under consideration may be incorporated in the filling dielectric in any way, for example by mixing with a liquid thermosetting resin, by coating insulating tapes with a solution or suspension of ferroelectric substances, or by any other known method.

The accompanying drawing shows, by way of example, a longitudinal cross-section of a waveguide according to the invention. In this drawing, 1 designates the helically coiled metallic wire constituting the internal conductor of the guide, 2 indicates the dielectric layer in which is incorporated a material having polar or ferroelectric molecules, 3 indicates the metallic fabric screen, 4 an insulating layer and 5 an external protective sheath.

55 I claim:

1. Circular waveguide having a helical wall, comprising a dielectric substance between the said wall and an external metallic screen, characterised in that there is incorporated in the dielectric substance an insulating material comprising polar or ferroelectric molecules which

has a relaxation effect in the frequency band transmitted by the guide such that the electrical thickness of the dielectric substance is constant over substantially the entire frequency band.

2. Waveguide according to claim 1, characterised in that the incorporated insulating material is chosen from the plumbates, the titanates, the niobates, the tungstates, the tantalates of alkaline-earth metals.

3. Waveguide according to claim 1, characterised in

that the incorporated insulating material is an organic material such as hydrated aluminium-guanidine sulphate.
